Atty.

UNITED STATES PATENT OFFICE.

JOSEPH McMONAGLE, OF CLEVELAND HEIGHTS, OHIO.

LAST.

Application filed September 15, 1923. Serial No. 662,895.

To all whom it may concern:

Be it known that I, JOSEPH McMONAGLE, a citizen of the United States, residing at Cleveland Heights, in the county of Cuyahoga and State of Ohio, have invented certain new and useful Improvements in Lasts, of which the following is a specification.

This invention relates to improvements in adjustable lasts, having for an object to provide a last including a minimum number of parts and having a wide range of adjustment.

Another object is to provide a last of this character in which the heel and sole portions may be independently adjusted and in which the adjusting means is extremely simple and reliable.

It is likewise an object to provide a last including a wedge block arranged upon the upper face of the sole portion, said block being removable to permit adjustment of the sole portion and to permit use of the last exclusive of said block as is often desired.

Other objects will be in part obvious and in part pointed out hereinafter.

In order that the invention and its mode of operation may be readily understood by persons skilled in the art, I have in the accompanying drawings and in the detailed following descriptions based thereon, set out one possible embodiment of the same.

In these drawings:—

Fig. 1 is a side elevation of the last;

Fig. 2 is a bottom plan view thereof;

Fig. 3 is a section taken on the line 3—3 of Fig. 1;

Fig. 4 is a vertical longitudinal section;

Fig. 5 is a side elevation showing a superposed wedge block in position;

Fig. 6 is a section taken on the line 6—6 of Fig. 5; and

Fig. 7 is a detail of the screw operating lever and reversible pawl.

Having more particular reference to the drawings throughout which similar characters of reference will designate similar parts, the last may be broadly stated as comprising an intermediate or body portion 8, carrying on one side an adjustable heel portion 9, at its other side a laterally expandable sole portion 10 and when desired a longitudinally adjustable wedge block 11 arranged upon the upper face of the sole portion.

The intermediate or body portion 8, is provided in its lower face with a longitudinal

under cut way or channel 12 which is adapted to receive a shouldered upstanding lug or head 13 carried by the extension 14 of the heel portion 9. As shown, this lug is threadedly engaged with a rotary screw 14', one end of which is disposed in a depending lug 15 formed in the channel 12 as indicated in Fig. 4. The outer end of the screw 14' carries a reversible pawl and ratchet mechanism 16 whereby the screw may be rotated and consequently adjust the heel portion longitudinally.

The sole portion 10 consists of two coacting parts preferably hollow, and having at their rear ends attaching lugs or ears 17, notched as shown for engagement with pivot or hinge pins 18 carried by the body portion as indicated in Figs. 1 and 2. The two sections are cut away as at 19 to permit positioning and manipulation of a reversible pawl and ratchet mechanism 20 by means of which a rotary screw 21 is operated. This screw as shown is mounted in a socket formed in the forward face of the body portion 8 in which is arranged a cross pin to retain the headed end 22 of the screw in proper position.

A wedge 23 is movable upon and with rotation of the said screw 21 and is engageable with a pair of spaced vertical pins 24 arranged in the sole portion and upon forward movements of the wedge it is obvious that the hinged parts of the sole portion will expand laterally. As indicated in Fig. 2, the forward lower faces of the sole portion are over-lapped to provide a smooth surface.

In order that the sole portion may be retained against expansion, a hook 25 is carried by one section and engageable with a pin 25' on the other section as shown in Fig. 2.

Often times it is essential that an additional block be inserted in the position I have indicated in Fig. 5 wherefore I provide the substantially wedge shaped block 11 movable along the upper surface of the sole portion under influence of a rotary screw 27 which is mounted in a socket 28 in the same manner as the preceding screw. The last named screw 27 is also removable so as to permit manipulation of the main screw 21. The removable feature also provides for use of the last without the wedge block 26, as is often desired. A pawl and

ratchet mechanism 29 is arranged upon the last named screw 27 for reasons which are apparent.

At times the expansion of the sole portion is unnecessary and at such times the two-sections may be secured together and the adjusting screw removed.

The intermediate or body portion 8 is provided with a socket 30 whereby mounting upon an ordinary standard or support may be effected.

Manifestly, the construction shown is capable of considerable modification and such modification as may fall within the scope of my claims, I consider within the spirit of my invention.

I claim:

1. An adjustable last, comprising an independent body portion having an undercut way formed longitudinally of its lower face, a screw arranged in the way and carried by the portion, a heel portion, an upstanding lug carried by the heel portion and movable longitudinally and guided within said way with rotation of the screw whereby to lengthen the last, and a sole portion carried by the body portion.

2. An adjustable last, comprising an independent body portion having an undercut way formed longitudinally of its lower face, a screw arranged in the way, a heel portion, an upstanding lug carried by the heel portion and movable longitudinally and guided within said way with rotation of the screw whereby to lengthen the last, an expandible sole portion arranged upon the body portion.

3. An adjustable last, comprising a body portion, a heel portion carried by said body portion, a two-part sole portion hinged to

the body portion, a screw carried by the body portion, and a wedge movable longitudinally with rotation of the screw and adapted to laterally expand the sole portion, and a wedge arranged upon the sole portion and adjustable to vertically expand the instep portion of the last independently of the remaining portions of the last.

4. An adjustable last, comprising an independent body portion, a pair of forwardly extending co-acting sole portions pivotally connected to the forward end of the body portion, a pair of depending spaced pins carried by the sole portions, a rearwardly extending heel portion slidably arranged in the body portion, a pair of screws, one of said screws being adapted to adjust the heel portion, and means carried by the second screw for laterally expanding the sole portion, said means comprising a wedge movable with rotation of the screw and acting upon the pins.

5. An adjustable last, comprising an independent body portion having a longitudinal under-cut way in its lower face, a pair of forwardly extending co-acting sole portions pivotally connected to the body portion, a rearwardly extending heel portion having a headed lug slidably arranged in the under-cut way in the body portion, a pair of screws, one of said screws being adapted to adjust the heel portion, a wedge carried by the second screw for expanding the two-part sole portion and a wedge block longitudinally adjustable upon the upper face of the sole portion.

In testimony whereof, I affix my signature.

JOSEPH McMONAGLE.
